SHIRT

Jerome N. Doumaux, Bayside, N. Y., assignor to
The B. V. D. Corporation, New York, N. Y., a
corporation of Delaware

Application July 2, 1940, Serial No. 343,618

4 Claims. (Cl. 2—115)

This invention relates to garments for the upper part of the body and is concerned more particularly with a garment of the shirt type embodying novel features which give it an improved appearance but without substantially increasing the cost of manufacture.

The new garment, in the form of a shirt suitable for sportswear, includes a yoke forming the upper portion of the garment in front and having a lower edge shaped to provide tabs for a pair of breast pockets. Preferably the lower edge of the yoke is formed of curved sections to give the garment an attractive appearance and this may be enhanced when the garment is made of patterned goods, by causing the patterns on the yoke and remainder of the garment to lie out of registry. The yoke and the panel below it forming the remainder of the front of the garment are connected together only along the lower edge of the yoke on either side and between the tabs, but provision is made to prevent the escape of articles upwardly from the pockets between the yoke and overlapped portion of the lower front panel.

For a better understanding of the invention, reference may be had to the accompanying drawing in which

Fig. 1 is a view of the new garment in front elevation, with certain parts removed;

Fig. 2 is an elevational view of the inner surface of a portion of the garment;

Fig. 3 is a perspective view on the line 3—3 of Fig. 1; and

Fig. 4 is a sectional view on the line 4—4 of Fig. 1.

The new shirt in the form illustrated comprises a back of conventional construction which extends to the tops of the shoulders and may either be a single piece of material or include a yoke 10. Connected along its side edges to the back is a lower front panel 11 which terminates a substantial distance below the top edge of the back and may, if desired, be formed of a pair of vertical sections having overlapping hems 12 connected by buttons and button holes. The lower front panel is provided with a pair of pockets 13 on either side of the central vertical line thereof and in the construction illustrated, each pocket is formed with a vertical pleat 14.

A yoke 15 is connected to the upper edge of the back and extends downwardly to overlap the top edge 16 of the lower front panel. This yoke has a lower edge 17 cut along arcuate lines and is so formed as to provide a pair of tabs 18 which serve to close the tops of the pockets and

5 terminate in points. Each tab is provided with a button hole 19 through which may be passed a button 20 on its associated pocket for the purpose of holding the tab down. The lower edge of the yoke is secured to the lower front panel on either side of and between the tabs, and the tabs are thus free to be raised and lowered.

The overlapped top edge 16 of the lower front panel is not stitched to the yoke, since such a line of stitching would detract from the appearance of the garment. Each tab is, therefore, provided with a liner 21 which is secured to the lower edge of the tab and extends upwardly between the yoke and the overlapped portion of the lower front panel to be connected to that portion, as, for example, along the upper edge thereof, by a line of stitching 22. With this arrangement, the raising of a tab does not provide an opening between the yoke and the overlapped portion of the lower front panel into the interior of the garment and an object inserted in the pocket cannot escape upwardly between the yoke and lower front panel.

In the construction shown in which the lower 25 front panel is made up of a pair of vertical sections, the yoke is similarly formed in two sections and the yoke sections and back are cut to provide a neck opening to the edge of which is secured a collar 23. The back, yoke, and lower front panel are similarly formed to provide armholes to the edges of which are secured sleeves 24.

The use of the yoke secured along its lower edge only to the lower front panel gives the shirt an attractive appearance and provides tabs for 30 closing the breast pockets and the provision of the liners makes it unnecessary to continue the lower front panel to the tops of the shoulders. Without such liners, the tops of the pockets would be open between the yoke and overlapped portion of the lower front panel, unless the panel continued to the tops of the shoulders. If that construction were used, there would be a double thickness of material throughout the part of the garment occupied by the yoke and this would 35 add substantially to the cost of manufacture because of the extra material and would make this portion of the garment uncomfortable. With the construction described in which liners are used, only a relatively small part of the garment includes two thicknesses of material and on buttoning down the tabs, the pockets are completely closed.

The use of the front yoke gives the garment a novel and attractive appearance which is capable of variation by cutting the lower edge of

the yoke in different forms. Also, when the shirt is made of patterned fabrics, variations in appearance may be obtained by offsetting the patterns in the yoke and lower front panel in various ways, as, for example, by cutting the lower front panel lengthwise of the goods and cutting the yoke on the bias.

I claim:

1. A body garment which comprises a back and a front having side edges which are shaped to define armholes and are connected together below the armholes, the front being made up of a yoke at the top and a lower front panel, the yoke having an upper edge which with the upper edge of the back is formed to provide a neck opening, said upper edges being connected together along the shoulders on opposite sides of the neck opening, the upper edge of the lower front panel lying above the level of the bottoms of the armholes and being overlain by the lower edge of the yoke, pockets attached to the lower front panel on opposite sides of the vertical median line of the front, a pair of extensions from the lower edge of the yoke overlying the tops of the pockets and providing closure tabs therefor, the yoke being secured along its lower edge to the lower front panel on either side of and between the tabs only, and sleeves secured to the edges of the armholes.

2. A body garment which comprises a back and a front having side edges which are shaped to define armholes and are connected together below the armholes, the front being made up of a yoke at the top and a lower front panel, the yoke having an upper edge which with the upper edge of the back is formed to provide a neck opening, said upper edges being connected together along the shoulders on opposite sides of the neck opening, the upper edge of the lower front panel lying above the level of the bottoms of the armholes and being overlain by the lower edge of the yoke, pockets attached to the lower front panel on opposite sides of the vertical median line of the front, a pair of extensions from the lower edge of the yoke overlying the tops of the pockets and providing closure tabs therefor, the yoke being secured along its lower edge to the lower front panel on either side of and between the tabs only, liners for the tabs secured to the free lower edges thereof and to portions

of the front panel overlapped by the yoke, and sleeves secured to the edges of the armholes.

3. A body garment which comprises a back and a front having side edges which are shaped to define armholes and are connected together below the armholes, the front being made up of a yoke at the top and a lower front panel, the yoke having an upper edge which with the upper edge of the back is formed to provide a neck opening, said upper edges being connected together along the shoulders on opposite sides of the neck opening, the upper edge of the lower front panel lying above the level of the bottoms of the armholes and being overlain by the lower edge of the yoke, pockets attached to the lower front panel on opposite sides of the vertical median line of the front, a pair of extensions from the lower edge of the yoke overlying the tops of the pockets and providing closure tabs therefor, the yoke being secured along its lower edge to the lower front panel on either side of and between the tabs only, liners for the tabs secured to the free lower edges thereof and to portions of the front panel overlapped by the yoke and lying above the upper end of the pocket, and sleeves secured to the edges of the armholes.

4. A body garment which comprises a back and a front having side edges which are cut to provide armholes and are connected together below the armholes, the front being formed of a yoke at the top and a lower front panel, each subdivided into right and left sections having overlapping vertical edges, the yoke having an upper edge which with the upper edge of the back is formed to provide a neck opening, said upper edges being connected together along the shoulders on opposite sides of the neck opening, the lower edge of the yoke overlapping the upper edge of the lower front panel and both said edges intersecting the armholes, a pocket on each section of the lower front panel below the upper edge thereof, and extensions from the lower edge of the yoke overlying the tops of the pockets and forming closure tabs therefor, the lower edge of the yoke being connected to the lower front panel on either side of and between the pockets and the upper edge of the lower front panel being free.
